MARGINAL FRAME FOR SPRING
ASSEMBLIES

Joseph A. Saval, Jamaica, N. Y., assignor to
Joseph Aronauer Incorporated, Brooklyn, N. Y.,
a corporation of New York

Application August 23, 1947, Serial No. 770,234

10 Claims. (Cl. 5—260)

1

The present invention relates to bed springs, seat springs and spring assemblies generally included in a variety of upholstered constructions. These spring structures are of the type comprising a pair of marginal frames in spaced relation, supporting a plurality of coil compression springs as a spring body. This invention concerns itself with the construction of said frame members out of flat metal strip; the rails of which frames lie in planes perpendicular to the longitudinal axes of the said coil springs.

Heretofore said frames were each a form lying in a single plane and determining a rectangle with rounded corners. Forming such corners is no simple operation and occasions much spoilage due to cracking and even breaking of the material while being stretched. It is this objection that the present invention avoids.

An object of the present invention is to provide a novel and improved construction for said marginal frames whose rail portions are coplanar, and whose corner formation is easy to make because substantially all stretching of the material is eliminated to accomplish the required form, as will be disclosed herein.

Another object hereof is to provide a corner construction for such frames which affords better maintainance of form to cushion and upholstered constructions.

A further object is to provide a novel and improved construction in frames for spring assemblies which is reasonably cheap to manufacture and efficient in carrying out the purposes for which they are designed.

In the accompanying drawings forming part of this application, similar characters of reference indicate corresponding parts in all the views.

Fig. 1 is a top plan view of a spring assembly embodying the teachings of this invention.

Fig. 2 is an end view thereof.

Fig. 3 is an enlarged fragmentary perspective view of the corner portion of a marginal frame included in the embodiment illustrated in Fig. 1.

Fig. 4 is a similar view of the corner portion of a marginal frame as heretofore made.

In the drawings, the numerals 15 and 15', indicate generally a pair of spaced marginal frames of rectangular form with corners rounded. These frames support a plurality of coil compression springs 16', which are secured to each other and to the frames by any means and suitable fashion, as for instance by tie wires, helical ties or clips, which are not shown, for they are well known in the art. The frames are of flat springy metal strip.

2

If the longitudinal axis of the respective coils 16', be deemed vertical, then the rails 18 and 19 of each frame are horizontally coplanar. The rounded corners of each frame, are each bent to an arc of a quarter circle, preferably of a radius equal to that of the end turn of a coil 16', so that the frame closely conform to the corner-positioned coils 16'. It is important to note that such rounded portions of the frames are twisted a quarter turn between such arc extremities indicated by points A and B and fully illustrated in Fig. 3. There are no bends in the frame material along such arc portions, so that a transversal across any of the rails of the frames is in a single plane, and a transversal across any arc portion of the frame lies in a plane normal to the plane of the rails.

One manner of constructing this marginal frame 15 or 15', is to take a straight metal strip, mark off the positions of the points A and B, then by torsional movement at these points, give the strip a quarter twist, and finally bend the respective portions between points A and B in a quarter circle, with said points at substantially the extremities of the arc. All this is extremely simple when compared with what need be done to make the corner bend shown in Fig. 4, where the flat metal strip is maintained coplanar throughout. Of course, the bend 20 at the corners in the structure of Fig. 3, need not be a quarter arc, and the frame form may be other than rectangular, as design and use may dictate.

Another method of making these marginal frames, is to take a straight metal strip, stand it on one of its longitudinal edges and form it into a frame form with rounded corners; said edge determining a plane in the finished frame. Now by torsional movement at points A and B, quarter twist the strip, whereby the rail portions alone 40 will assume coplanar horizontal position. The meeting edges of the strip when formed into the frame, and prior to the torsional twisting operations, may be secured to each other in any suitable manner, as by welding or otherwise.

45 It is to be noted that the center lines of the rails 18 and 19, along their plane, are tangent to the arc into which the corner portions are bent, and that the plane of said rails is intermediate the edges of the corner portions of the frame. This affords overlapping of a portion of the end turns of intermediate marginal coils 16', by the rails of the frame, and contact of a portion of the end turns of the corner positioned coils 16', with the concave surfaces of the frame corner 55 bends, respectively.

I have stated herein that the marginal frames are made of flat strip material. It shall be understood that such designation both in the specification and claims shall include strip, meaning material whose thickness is substantially smaller than its width, and whose cross section may for instance be rectangular with square or rounded corners, or with ends rounded as when performed of flattened round stock, or even elliptical whose cross section's minor axis is substantially smaller than its major axis, also though mentioned as flat, also same shall include a strip having transverse corrugations as at 22, if such is desired to lend greater flexibility to the structure.

This invention is capable of numerous forms and various applications without departing from the essential features herein disclosed. It is therefore intended and desired that the particular embodiment herein be deemed illustrative and not restrictive and that the patent shall cover all patentable novelty herein set forth; reference being had to the following claims rather than to the specific description herein to indicate the scope of this invention.

I claim:

1. In a spring assembly of the character described, a marginal frame made of strip material, comprising straight sides and bent corner portions; said frame determining a surface; the wide sides of the strip material constituting all the side portions of said frame, being substantially parallel to said surface, and the wide sides of the strip material constituting all the corner portions of said frame, being substantially perpendicular to said surface and a plurality of spring components carried on said frame.

2. A spring assembly as defined in claim 1, wherein the marginal frame has pairs of spaced quarter-turn torsional twists formed therein, to determine the respective corner portions thereof.

3. A spring assembly as defined in claim 1, wherein the marginal frame is made of a single strip having pairs of spaced quarter-turn torsional twists formed therein, to determine the respective corner portions thereof.

4. A spring assembly as defined in claim 1, wherein the wide sides of the strip material constituting all the side portions of the frame, are substantially coplanar.

5. A spring assembly as defined in claim 1, wherein each of the corner portions of the frame are of actual form whose respective concave surfaces are inward of the frame remote external perimeter and wherein are included corner positioned spring components; said components being compression coil springs whose longitudinal axes are perpendicular to the mentioned surface; a portion of the end turn of each of said corner-positioned coil springs being in contact with the concave surface of the frame at the respective corner portions of said frame.

6. In a spring assembly of the character described, a pair of opposite, spaced marginal frames, each made of strip material, comprising straight sides and bent corner portions; each of said frames determining a surface, respectively; the wide sides of the strip material constituting all the side portions of the first frame, being substantially parallel to the surface determined by the first frame; the wide sides of the strip material constituting all the corner portions of the first frame, being substantially perpendicular to the surface determined by the first frame; the wide sides of the strip material constituting all the side portions of the second frame, being substantially parallel to the surface determined by the second frame; the wide sides of the strip material constituting all the corner portions of the second frame, being substantially perpendicular to the surface determined by the second frame and a plurality of spring components carried by said frames whereby the said frames are maintained apart.

7. A spring assembly as defined in claim 6, wherein each marginal frame has pairs of spaced quarter-turn torsional twists formed therein, to determine the respective corner portions thereof.

8. A spring assembly as defined in claim 6, wherein each marginal frame is made up of a single strip having pairs of spaced quarter-turn torsional twists formed therein, to determine the respective corner portions thereof.

9. A spring assembly as defined in claim 6, wherein the wide sides of the strip material constituting all the side portions of the first frame, are substantially coplanar and wherein the wide sides of the strip material constituting all the side portions of the second frame, are substantially coplanar.

10. A spring assembly as defined in claim 6 wherein each of the corner portions of the frames are of arcual form whose respective concave surfaces are inward of the frame remote external perimeter and wherein are included corner-positioned spring components; said components being compression coil springs whose longitudinal axes are transverse the respective surfaces determined by the frames; a portion of each end turn of each of said corner-positioned coil spring being in contact with a concave surface of each frame respectively at the respective corner portions of said frames.
